CLAIM

The ornamental design for a control panel for vehicle heating and air conditioning systems, as shown and described.

DESCRIPTION

(22) Filed: **Jul. 6, 2012**

FIG. 1 is a perspective front view of a control panel for a vehicle heating and air conditioning system showing the design;

(51) **LOC (9) Cl.** 12-16

FIG. 2 is a top view of the control panel for a vehicle heating and air conditioning system of FIG. 1;

(52) **U.S. Cl.** **D23/324**

FIG. 3 is a front view of the control panel design of FIG. 1;
FIG. 4 is a right end view of the control panel design of FIG. 1;

(58) **Field of Classification Search** D23/314,

FIG. 5 is a left end view of the control panel design of FIG. 1;
FIG. 6 is a bottom view of the control panel design of FIG. 1;
and,

D23/324, 325, 326, 327; D10/50, 49, 60,
D10/103; D12/400, 192; D14/247, 258;

361/694; 236/1 C; 62/131

See application file for complete search history.

FIG. 7 is a rear view of the control panel design of FIG. 1.

(56) **References Cited**

The broken lines are provided solely for illustrative purposes and form no part of the claimed design.
